UNITED STATES PATENT OFFICE

162,874

SEA ANCHOR

Paul W. Polenz, La Jolla, Calif.

Application August 3, 1949, Serial No. 4,278

Term of patent 14 years

(Cl. D71—1)

To all whom it may concern:

Be it known that I, Paul W. Polenz, a citizen of United States of America, residing at La Jolla, county of San Diego, and State of California, have invented a new, original, and ornamental Design for a Sea Anchor, of which the following is a specification, reference being had to the accompanying drawing, forming a part thereof, wherein:

Figure 1 is a view in side elevation of a sea anchor, showing my new design.

Figure 2 is a view partly in side elevation and partly in vertical section of the anchor.

Figure 3 is a view in front elevation of the anchor.

Figure 4 is a view in rear elevation of the anchor, and

Figure 5 is a perspective view of the anchor.

I claim:

The ornamental design for a sea anchor, as shown.

PAUL W. POLENZ.
